UNITED STATES PATENT OFFICE.

GILBERT PONTBRIAND, OF WEST WARREN, MASSACHUSETTS.

HYDROCARBON-BURNER.

1,113,826.

Specification of Letters Patent. Patented Oct. 13, 1914.

Application filed April 3, 1913, Serial No. 758,679. Renewed May 14, 1914. Serial No. 838,468.

To all whom it may concern:

Be it known that I, GILBERT PONTBRIAND, a citizen of the United States, residing at West Warren, in the county of Worcester and State of Massachusetts, have invented 5 certain new and useful Improvements in Hydrocarbon-Burners; and I do declare the following to be a full, clear, and exact description of the invention, such as will enable others skilled in the art to which it 10 appertains to make and use the same.

This invention relates to improvements in hydrocarbon burners and more particularly to the fuel feeding and mixing mechanism 15 thereof.

One object of the invention is to improve the fuel feeding and mixing mechanism shown in the United States Patent No. 1,042,821 granted to me October 29, 1912, 20 whereby the same is rendered more efficient and reliable and may be more readily controlled.

With this and other objects in view, the invention consists of certain novel features 25 of construction, and the combination and arrangement of parts as will be more fully described and claimed.

In the accompanying drawings; Figure 1 is a vertical sectional view of a stove 30 showing my improved burner and fuel feeding mechanism applied thereto; Fig. 2 is a horizontal sectional view of the same taken on the line 2—2 of Fig. 1; Fig. 3 is a vertical cross sectional view of the burner taken 35 on the line 3—3 of Fig. 2; Fig. 4 is a detail vertical sectional view of one of the burner tips removed from the burner; Fig. 5 is a part side view and part longitudinal vertical section of a portion of my improved 40 fuel feeding and mixing mechanism; Fig. 6 is a detail perspective view of the injector nozzle forming part of the fuel feeding and mixing mechanism and showing the parts thereof separated; Fig. 7 is a similar 45 view of the nozzle looking toward the inner end thereof; Fig. 8 is a plan view of a modified form of burner having my improved feeding and mixing mechanism applied thereto; Fig. 9 is a longitudinal vertical sectional view of the burner and feeding mechanism shown in Fig. 8; Fig. 10 is a cross sectional view of the same; Fig. 11 50 is a plan view of another modified form of burner having my improved fuel feeding and mixing mechanism applied thereto; Fig. 12 is a cross sectional view of the burner 55

and feeding mechanism shown in Fig. 11; Fig. 13 is a perspective view of another form of burner having my improved feeding and mixing mechanism connected therewith; Fig. 14 is a horizontal sectional view of still another form of burner showing a modified construction of the fuel feeding and mixing mechanism.

Referring more particularly to the first 65 three figures of the drawings, 1 denotes my improved burner which comprises a hollow body having a bottom plate 2, side and end flanges 3 and a top plate 4 spaced above the bottom plate to form a fuel compartment 5. In the bottom plate 2 and top plate 4 are formed series of aligned apertures 6 with which are engaged ventilating tubes all of which structure corresponds to the structure of the burner shown in the 75 patent herein referred to.

In the top plate 4 are formed series of burner openings 8 in which are arranged burner tips 9 in the form of threaded valve plugs constructed in upper and lower adjustable sections having fuel passages 10 and which are otherwise constructed and arranged for operation as shown and described in United States Patent No. 990,164 granted to me April 19, 1911, and a further 85 description of which in the present instance is not thought to be necessary.

Connected with the body of the burner at one end is a fuel mixing chamber 11 which is connected at its outer end with a fuel supply chamber 12, to the outer end of which is connected a steam supply pipe 13. The chamber 12 is connected with the outer end of the mixing chamber or tube 11 by a union or other suitable coupling as shown in Fig. 95 5 of the drawings and formed integral with the inner end of the chamber 12 is a gas or oil injecting tube 14 in which is arranged a controlling valve 15 and on the outer end of which is arranged a union or other form of coupling 16 by means of which a heating coil may be connected with said injecting tube. One end of the injecting tube 14 opens into the chamber 12 near the inner end thereof and this end of the injecting tube is interiorly threaded to receive an injector nozzle 17 comprising a short tube which flares toward its outer end and has its inner end closed by a plate having therein a series of small perforations 18 through 100 which the oil or gas passes from the injector tube into the nozzle 17. Adjustably 105

supported in the outer end of the nozzle 17 is a spreader or deflecting plate 19 which is formed on the outer end of a shank 20 the inner end of which has a threaded engagement with a centrally disposed threaded passage 21 in the inner end plate of the nozzle. The deflecting plate or spreader is provided on its outer side with a screw driver slot 22 to permit the shank to be 5 screwed inwardly or outwardly thus adjusting the spreader 22 whereby the fluid is discharged from the nozzle in the form of a spray of greater or less fineness. The oil or gas when discharged into the tube or 10 mixing chamber 11 from the nozzle 17 mixes with the steam therein and is discharged therefrom, and into the body of the burner 15 through perforations 11^a in the tube 11.

Arranged in the lower side of the chamber 20 12 near its connection with the steam supply pipe 13 is a drain pipe 23 having a cut-off valve 24 as shown. The chamber 12 is also provided with a controlling valve which may be of any suitable construction. 25 In the present instance the chamber 12 has arranged therein a partition 25 having therein a valve seat 26 with which is adapted to be engaged a steam controlling valve 27 whereby the passage of steam through the 30 chamber 12 to the fuel mixing chamber 11 may be controlled.

The valve 27 is provided with a stem 28 which has a threaded engagement with a screw plug 29 arranged in a threaded aperture 30 in the lower side of the chamber 12 in line with the valve seat 26. The stem 28 of the valve passes through an ordinary stuffing box in the plug 29 whereby a fluid tight connection is formed between the 40 valve stem and the opening in the plug.

Connected with the injector tube 14 by the coupling or union 16 hereinbefore described is an oil heating and gas generating coil 32 which is designed to occupy a position 45 over the burner and which may be constructed in various shapes and designs to correspond with the construction and arrangement of the burner to which the same is applied. In Figs. 1, 2 and 3 of the drawings the coil 32 is in the form of a plurality of loops arranged one within the other and of such size as to lie above the two outermost rows of burner tips whereby the flame from these tips has a direct contact with 50 the loops of the coil as clearly shown in Figs. 2 and 3 of the drawing. By thus arranging the coil 32 it will be seen that the oil will be effectually heated and converted into gas after the burner is lighted and as 55 fast as the gas is consumed by the burner.

In order to generate sufficient gas for starting the burner, I provide an auxiliary heating coil 33 the ends of which are connected to the oil supply pipe 34 to which 60 the outer end of the coil 32 is connected.

The auxiliary heating coil 33 may be arranged at any suitable location in the oil supply pipe 34 and in the inlet end of the coil 33 is arranged a cut-off valve 35 while in the oil supply pipe 34 between the points where the ends of the coil 33 connect therewith is arranged a cut-off valve 36. In starting the burner, a lamp or torch of any suitable character is placed beneath the coil 33 after which the valve 36 in the oil pipe is closed and the valve 35 in the coil pipe is opened thus causing the oil to flow through the coil 33 wherein the oil is primarily heated by the lamp or torch and sufficient gas thus generated to supply the burner until the main generating coil 32 has become heated to a sufficient extent for converting oil passing therethrough into gas. After the main coil 32 has thus been heated to a sufficient extent the valve 35 in the auxiliary coil is closed and the valve 36 in the oil supply pipe opened, thus causing the oil to flow directly through the supply pipe to the main generating coil as will be readily understood.

In Figs. 8, 9 and 10 of the drawings is shown a burner 37 having a slightly different arrangement of burner tips from that shown in the first three figures of the drawing and in which the main gas generating coil 38 is simplified. In this instance the coil 38 has but one loop but is otherwise the same as the coil 32 hereinbefore described.

In Figs. 11 and 12 is shown another slightly modified form of burner 39 wherein the fuel receiving space shown in the first figures of the drawing is dispensed with and in the bottom 40 of which is formed a central fuel passage 41 and a series of laterally extending branch passages 42 which connect with the main passage and which have their outer ends turned upwardly and opening through the upper side of the bottom of the burner to provide fuel outlets which are threaded to receive the burner tips or valves as shown. Arranged through the bottom 40 of the burner between the outlet openings of the branch passages 42 are ventilating apertures 43 which correspond to and are provided for the same purpose as the air or ventilating passages shown and described in the first form of the invention. The gas generating coil 44 for the burner 39 is constructed in the same manner as the gas generating coil 37 shown in Fig. 120 8 of the drawing.

In Fig. 13 is shown another modified form of burner comprising a hollow head 45 to one side of which midway between its ends is connected the chamber 12 of the feeding and mixing mechanism. The head 45 forms a mixing chamber and has thereon series of nipples 46 to which are connected burner tubes 47 which are spaced apart and arranged in parallel relation as shown. In 130

the upper sides of the burner tubes 47 are formed series of gas discharging apertures in which are arranged my improved burner tips or valves 9 hereinbefore described. In this form of the burner there is also provided a heating and generating coil which is not shown in the present instance but which may be arranged over the burner tips in any suitable manner and connected with 10 the outer end of the injector tube as will be readily understood.

In Fig. 14 of the drawings is shown another modified form of burner 48 which comprises a solid block of metal having 15 therein a centrally disposed passage 49 which opens through one end of the block and has connected therewith at its outer end at points between its ends outwardly projecting gas discharging passages 50 the ends 20 of which curve upwardly and open through the upper side of the block in the same manner as the branch passages 42 of the form of burner shown in Figs. 11 and 12 and in which are arranged my improved burner 25 tips 9. The block 48 has also formed therein a steam generating passage 51 which opens through and begins at one end of the block 48 and extends inwardly parallel to one side of the block as shown at 52, thence 30 across the block, beyond the inner end of the passage 49 as shown at 53 and thence back through the opposite side of the block as shown at 54 and has its inner end connected with or opening into the central passage 49 as shown at 55. It will thus be seen 35 that the passage 51 passes entirely around through the block so that the fluid passing through this passage is heated and vaporized or turned to steam by the heated block 40 when the burner is in use. In this form of the burner the passage 49 is designed to receive oil or gas which is supplied thereto through an oil or gas conducting pipe 56 which is connected with the outer end of the 45 passage while the passage 51 is designed to receive water which is supplied thereto through a water conducting pipe 57 connected with the outer end of the passage. The water in passing through the passage 50 51 is vaporized or turned to steam before

being discharged into the oil or gas passage 49, said passage thus forming a mixing chamber in which the steam and oil or gas are mixed before being discharged to the burner tips. In the burner 48 are also 55 formed ventilating passages 58 which correspond to and are provided for the same purpose as the ventilating passages shown and described in the other forms of the invention.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as claimed.

Having thus described my invention, what I claim is:

In a burner of the character described, a body having therein burner openings, a fuel mixing chamber connected with said body, 75 a fuel supply chamber connected with said mixing chamber, a valved gas or oil injecting tube connected with said supply chamber, an injector nozzle arranged in said tube and comprising a short tube having a flared 80 discharge end and having its inner end closed and provided with perforations, said inner end having a threaded passage, a spreader arranged in the outer end of said nozzle and having a threaded stem engaged 85 with the threaded aperture in the inner end of the nozzle whereby the spreader is adjusted in the outer end of the nozzle, a gas or oil supply pipe connected with said injector tube, a steam pipe connected with said 90 fuel supply chamber, and a steam controlling valve arranged in said chamber.

In testimony whereof I have hereunto set my hand in presence of two subscribing witnesses.

GILBERT PONTBRIAND.
